UNIVERSAL LIQUID DISPENSER

Lawrence G. Bates, Shaker Heights, Ohio, assignor to
Continental Say-When Corporation, Cleveland, Ohio,
a corporation of Ohio

Application November 8, 1952, Serial No. 319,541

5 Claims. (Cl. 222—401)

Liquid dispensers of the type involving a hand-operated pump mounted on a container-closure as successfully used on bottles of size up to a gallon, if applied to larger containers lose their effectiveness. I have found that this is not due to a deficiency in size of pump, as might prima facie be supposed; but it is due to a peculiar relationship with the air in the container. A dispenser mounted on the container-closure and which is interchangeably applicable to containers of various size, as bottles, demijohns, carboys, etc., is an important desideratum. In the present invention this is now successfully attained. And the construction is not complicated, and it does not require substitution of parts on being moved from one container to another. Other objects and advantages of the invention will appear from the following description.

To the accomplishment of the foregoing and related ends, said invention, then, comprises the features hereinafter fully described and particularly pointed out in the claims, the following description and the annexed drawing setting forth in detail certain illustrative embodiments of the invention, these being indicative, however, of but a few of the various ways in which the principle of the invention may be employed.

In said annexed drawing:

Fig. 1 is a view of an embodiment of the invention, partly in perspective, and chiefly in vertical section; and

Fig. 2 is a broken sectional view corresponding to the upper and lower portions of Fig. 1, and showing a modification, on greatly enlarged scale.

In general, the device involves a closure or stopper 2 to coact with the neck 3 of a bottle, demijohn, carboy, etc., and this preferably involves a cork or rubber stopper-like body within which is a stem 5 supporting at its top a plate 6 in the form of a stationary piston. Cooperating with the plate is a reciprocable cylinder 7 which is manually operated by being pressed down, and a coil spring 8 inside serves to return the cylinder to its upper or extended position when released by the operator. Suitable packing 9 is provided for the piston against which the reciprocable cylinder operates. At the top of the cylinder is a port 10 which is for control by the operator's finger pressing thereover at appropriate times. A guide stem 11 is secured to the top of the cylinder 7, and a bore 12 leads from the port 10 to an opening 13 into the cylinder. The guide stem 11 is closed below, and in the movement of the cylinder 7 travels air-tight in the guideway in stem 5. The lower end of the guideway is headed at 14 to prevent its being withdrawn from the stem. Thus, the cylinder 7 with its guide 11 may be reciprocated up and down in the function of the device, and the skirt of the cylinder is of such a diameter as to pass over the neck of the container 3 to the full limit of the excursion movement. In the closure also is a discharge tube 15, this being set in air-tight relation, in the closure or stopper, and the outer end of the tube is suitably bent to provide a properly directed discharge end 16. The inner end of the tube 15 forms an extension 17 in the container, and where desired a suitable extension 18 may be secured thereto, and the

2

latter may be a flexible non-corroding tube. The communication between the pump chamber 7 and the container for passage of air in the operation of the pump, is a bore 19. This is peculiar, in that it is of great length and small caliber. For instance, its diameter may satisfactorily be on the order of 0.03 in. As the operator presses the pump cylinder down, his forefinger being on the port 10, the air in the cylinder is expelled through the bore 19 into the top of the container. On relaxing the pressure and coverage of the port 10, the cylinder 7 rebounds, and the operator may then immediately repeat the pressing down of the cylinder and force more air through the bore 19. The air flow from the pump through such restricted caliber is quite adequate because of the relatively high pressure in the pump as compared with that in the container, and back-flow on rebound with the pump is negligible because of the resistance in the passage to flow under relatively low pressure. Thus, by a few strokes of the pump cylinder, pressure is built up in the container sufficient to force the liquid from the lower portion of the container to the discharge tube 15 to a desired receptacle. Thus, the peculiarity of the passageway 19 is its providing a means for retarding the rate of flow of air from the container to the pump. When the pump is quiescent, equalization of air pressure between the pump chamber and the container can take place ultimately. But, the retarding means works effectively against back-flow from low pressure area to high pressure area while the pump is operating. Such a means for retarding the rate of flow from the container to the pump is seen to be durable without possibility of change in service, as the air passageway does not depend upon moving contact surfaces subject to wear and change. The function here involved is also one which could not be attained by valve means, as it is required that there be a passageway open continually without interruption.

The manner of operation of the device is understood from the foregoing. To withdraw a charge of liquid from the container to a receptacle held under the discharge 16, the operator closes the port 10 with his forefinger and presses the cylinder 7 down and then releases. The downward movement of the cylinder forces the air content of the cylinder through the passageway 19 into the top of the container, and depending upon the space there, the pump cylinder is pressed down in repetition sufficient to effect discharge of the desired amount of liquid, and in each reciprocation the restricted bore 19 provides passage of the high pressure air from the pump, but back-flow from the container is obviated.

The feature of the passage for communication between the pump cylinder and the container being a free way for high pressure air but retarding back-flow, a modification of the passageway may be provided in the form of construction as shown in Fig. 2. Here, the cylinder 7 and the port 10 and coil spring 8 are the same as shown in Fig. 1, and the fixed piston in relation to the stem of the stopper or closure are the same, and likewise the discharge conduit or tube. The difference here is that the stem 5' instead of having a bore 19 as in Fig. 1, is solid. And the guide 11' is tubular throughout, and has the same opening 13 into the pump cylinder. The guide 11' at its lower end, like the guide in Fig. 1, has an air-tight sliding fit in the stem 5', and to prevent its being withdrawn therefrom in upward movement, the retaining head 14' is in the form of a screw. A peculiarity here is that combined means are involved for providing such retaining head, and at the same time providing the means for retarding the rate of flow of air from the container to the pump. The screw 14' has a size relation to the tube 11' such that the threads of the screw as set into place bite superficially into the wall of the tube, and leave a spiral air passage in the threading

between the screw body and the wall of the tube, instead of being in tight closing off relation. Thus, there is again a small caliber bore, here in spiral form from the interior of the cylinder 7 by way of the opening 13, between the screw body and the tube wall, and ending at the opening 20 below, such opening being the outlet of the spiral passageway around the screw body. The operation of this form of the device is the same as described with respect to the form of Fig. 1.

Other modes of applying the principle of the invention may be employed, change being made as regards the details described, provided the features stated in any of the following claims, or the equivalent of such, be employed.

I therefore particularly point out and distinctly claim as my invention:

1. In a liquid dispenser having a pump supported on a closure for a container opening and a discharge tube in such closure which communicates between liquid in the container and a point of discharge outside, guide means for the pump relative to the closure, finger-controlled means for admitting air from outside into the pump, and means for admitting pressure air from the pump into the container and for retarding the rate of flow from the container to the pump embodying a continually open helical connecting passageway.

2. In a liquid dispenser, the combination set forth in claim 1 including means for forming the connecting passageway and preventing upward withdrawal of said guide means.

3. A liquid dispenser comprising pump means having a normally open finger closable passage communicating with the atmosphere and providing ready direct supply of air therethrough to the pump chamber, and mounting means attached to said pump means adapted to support the latter on a container for liquids at the container outlet, said mounting means including a continually open air conduit which provides communication between the pump chamber and the interior of such container, the air conduit being of smaller section than said finger closable passage

and of such fine caliber as to resist the flow of low pressure air through the same, whereby such conduit is effective to pass readily high pressure air from such pump means to the container and to retard reverse flow of relatively low pressure air.

4. A liquid dispenser comprising pump means having a reciprocable pumping member and a normally open finger closable passage communicating with the atmosphere for the direct supply of air therethrough to the pump chamber, mounting means attached to said pump means adapted to support the latter on a container for liquids at the container outlet, guide means secured to said pumping member for reciprocation therewith and extending through said mounting means, said guide means being hollow and provided with openings serving to form an air passage between the pump chamber and the container interior through the guide means, and means restricting a portion of such air passage to a relatively small section effective to resist the flow of low pressure air through the same, whereby such restricted portion readily passes high pressure air from the pump means to the container and retards reverse flow of relatively low pressure air.

5. A liquid dispenser as set forth in claim 4 in which said guide means is tubular and a stop member is superficially screw-threaded into an end of the same, the threads thereby defining with the wall of the guide means the restricted portion of the air passage between the pump means and container, said stop member having a head which engages the mounting means to limit withdrawal of the guide means therefrom.
